UNITED STATES PATENT OFFICE

HANS CHRISTIAN HANSEN, OF WEST HARTFORD, AND ALFRED JOHN BENNETT, OF HARTFORD, CONNECTICUT, ASSIGNORS TO THE ARROW-HART & HEGEMAN ELECTRIC COMPANY, OF HARTFORD, CONNECTICUT, A CORPORATION OF CONNECTICUT

PUSH SWITCH

Application filed May 5, 1931. Serial No. 535,224.

This invention relates to switches which are adapted to be operated by pressure applied to a spring pressed plunger. More particularly the invention relates to a switch which is normally biased in one position but which upon application of pressure snaps to another position and upon removal of that pressure returns to its original position. The switch is particularly useful in controlling lighting circuits for illuminating closets, iceboxes and the like wherein it is desired to illuminate the interior upon opening of the door and to extinguish the light by closing the door. However, the switch is not limited to such use, but is applicable to use in many other situations.

It often happens in mounting switches of the above type that slight inaccuracies creep in which would permit the door to impart greater movement than necessary to the switch operating member. Unless provision is made to take care of inaccuracies in mounting and expansion and contraction of the members adjacent the switch and upon which it is mounted, the switch may become permanently damaged by excessive movement of the switch operating member.

Therefore, it is an object of this invention to provide a switch of the above type with means to take up any excess movement of the door or other device for switch actuation, so that the switch mechanism will not be damaged by such excess movement.

Another object of the invention is to provide a compact easily manufactured substantially built switch of the above type. Other objects and advantages of the invention will appear as it is described in connection with the accompanying drawing. In the drawing:

Fig. 1 is an elevation view of the invention with the operating mechanism shown in mid-section and the switch contacts in closed circuit position.

Fig. 2 is a view similar to Fig. 1 but with the switch in open circuit position.

Fig. 3 is a view similar to Fig. 1 but showing the switch parts in the position taken by them when they are given an excess movement by the door or other actuating device.

Fig. 4 is a sectional elevation view of the invention with the section taken on the line 4—4 of Fig. 1.

Fig. 5 is a detail view of the plunger.

Referring to the drawing the switch proper is of the type shown in the Guett Patent 1,511,809 patented October 14, 1924, in which a laminated insulating base 10 contains suitable contacts 12 which are adapted to be bridged by an anti-friction roller 14 which moves in a switch cavity 15 in the insulating base. This roller is moved by a switching member 16, through the agency of a switch operating lever 18 as will hereinafter be more fully described. A metallic casing 20 embraces the insulating base and together with the rivets 22 confines the laminations of the base. There is an opening in the top of the metallic casing 20 in which is secured an externally threaded sleeve 24 for mounting the switch in the desired location.

A hollow cylindrical plunger 26 is slidably received within the sleeve 24. This plunger has a pair of diametrically opposed slots 27 formed in its lower end through which projects a spindle 28 mounted diametrically in the sleeve 24 and upon which is a pivotally mounted switch operating bell crank lever 18. One arm 18a of this lever engages in an aperture 29 in the bottom part of the plunger, this aperture 29 being spaced midway around the plunger between the slots 27. The other arm 18b of the bell crank lever 18 engages with the switching member 16 to cause movement thereof in the manner described in the Guett Patent 1,511,809.

From the foregoing it will be apparent that if the plunger is moved up and down within the mounting sleeve the arm 18a will be caused to rotate about the spindle 28 and hence will cause the arm 18b to move and throw the switching member 16 from "off" to "on" position and vice versa.

The range of movement of the bell crank operating lever 18 is controlled by the following means.

The upward movement of the plunger is limited by the lower end of the slots 27 abutting the spindle 28 and also by arm 18b abutting the inside of the sleeve 24. The

downward movement of the plunger is limited by the upper end of the slots 27 abutting the spindle and also by a shoulder 30 on the upper end of the plunger 26 abutting the top of the sleeve 24.

- 5 In order to prevent the spindle 28 from being deformed and also to protect the whole switch against injury by reason of excess pressure being put upon the plunger 26, we provide the following mechanism. An auxiliary coil spring 34 is placed within the plunger 26 with its lower end resting upon an inwardly directed shoulder 32 formed midway down the inside of the plunger. The upper end of this coil spring presses against 10 a button 36 which is located in top of the plunger and is movable relative thereto. The lower part 36a of this button is enlarged and is of substantially the same diameter as the inside of the plunger.
- 15 In assembling the operating mechanism, the button 36 is placed within the plunger 24 with the auxiliary coil spring 34 under tension. Then the upper end of the plunger is turned over the enlarged lower portion 20 36a of the button, thus sealing the button within the plunger with its small upper end 36b projecting beyond the end of the plunger.
- It is desirable that the switch should be at 25 all times biased to closed circuit position. For this purpose we provide a main coil spring 38 of less strength than the auxiliary spring 34 and having a smaller diameter than the auxiliary spring and working within the auxiliary spring. It is essential that both 30 of these springs be of greater strength than the switch spring 16s as will hereinafter appear. The upper end of this main spring presses against the enlarged bottom of the button 36 while the lower end of the spring 35 fits into a cylindrical cup 40 located in the bottom of the plunger, the diameter of the cup being approximately the same as the inside diameter of the lower end of the plunger. The bottom of the cup rests on the spindle 28 and therefore the cup is held 40 against downward movement relative to the sleeve 24 as the main spring 38 is compressed when the plunger is depressed. In order 45 that the bell crank lever may move freely a slot 42 is cut in the bottom of the cup to permit the bell crank lever to rotate without engaging the bottom surface of the cup. However, this slot 42 serves to hold the bell 50 crank lever from axial movement along the spindle.

The operation of the device will now be described. When the switch is assembled the parts assume the position shown in Fig. 69 1. In this figure the main spring pressing the cup 40 against the spindle 28 and pressing the button 36 against the overturned top of the plunger, causes the plunger 24 to take its uppermost position. This causes the arm 65 18b of the switch operating lever 18 to take

its left hand position. See Fig. 1. Now when pressure is exerted upon the button, the pressure is transmitted through the auxiliary spring to the plunger which is caused to descend by reason of the strength of the auxiliary spring being greater than that of the spring of the switch mechanism. Depression of the plunger causes the bell crank lever 18 to rotate the arm 18b of the lever eventually causing the switching member 16 70 to move to open circuit position as shown in Fig. 2. When the plunger has been depressed as far as possible the upper ends of the slots 27 abut the spindle 28 and the shoulder on the outside of the plunger rests upon the top of the mounting sleeve 24. Further depression of the plunger is therefore impossible without damage to the switch.

However, due to inaccuracies in mounting the switch, or due to overthrow of the door 85 or other object with which the plunger is co-operating, there may be a tendency to move the plunger further than is necessary to operate the switch. But, since the door presses against the button 36 and not against the plunger, the button may be moved further, compressing the auxiliary spring and taking up the overthrow and thereby saving the switch from damage. The position of the parts when this overthrow is taken up is 90 shown in Fig. 3. Upon movement of the door away from the button the parts assume the position of Fig. 1 by reason of the strength of the main spring 38 being great enough to raise the plunger against the bias of the 100 switch spring.

The switch is particularly useful in connection with a door, and in such a case would be mounted so that the closing of the door would depress the plunger and open the 105 switch and opening of the door would release the plunger and allow the switch to be opened automatically by the pressure of the main spring causing the plunger to rise. However, the switch is in no wise limited to this 110 use but may be varied in innumerable ways to suit varieties of situations.

From the foregoing it will be seen that we have constructed a compact switch operating mechanism for use with a conventional type 115 of snap switch which will take up all overthrow which might normally occur due to expansion and contraction of parts cooperating with the switch or due to inaccuracy in mounting the switch. Obviously the switch 120 mechanism per se may be varied widely within the scope of the invention. Many changes in form will occur to those skilled in the art, therefore we do not limit ourselves to the specific embodiment of the switch shown 125 herein.

We claim:—

1. An electric switch comprising a casing, a sleeve mounted on said casing, a plunger slidably engaged with said sleeve, a spindle 130

journalled in said sleeve and limiting the movement of said plunger, a button in said plunger and movable relatively thereto, main and auxiliary springs in said plunger constantly urging said plunger and button in one direction, and switch mechanism engaged and operated by said plunger.

2. An electric switch comprising a casing, a sleeve mounted on said casing, a plunger 10 slidably engaged with said sleeve, a spindle journalled in said sleeve, and limiting the movement of said plunger, a button in said plunger and movable relatively thereto, main and auxiliary springs in said plunger constantly urging said plunger and button in one direction, and switch mechanism engaged and operated by said plunger.

3. An electric switch comprising a casing, 20 a sleeve mounted on said casing, a plunger slidably engaged with said sleeve, a spindle journalled in said sleeve and passing through a slot in said plunger to limit the movement thereof, a button in said plunger and movable relatively thereto, main and auxiliary springs 25 in said plunger pressing against said button and constantly urging said plunger and button in one direction, a switch lever mounted on said spindle, and switch mechanism actuated by said lever as said plunger is moved.

In testimony whereof we have signed our names to this specification.

HANS CHRISTIAN HANSEN.
ALFRED JOHN BENNETT.
